UNITED STATES PATENT OFFICE.

JAMES J. ROHAN, OF ST. LOUIS, MISSOURI, ASSIGNOR OF ONE-HALF TO THOMAS W. CUMMINGS, OF ST. LOUIS, MISSOURI.

CAR-HEATER.

1,308,194.

Specification of Letters Patent.

Patented July 1, 1919.

Application filed June 8, 1918. Serial No. 238,890.

To all whom it may concern:

Be it known that I, JAMES J. ROHAN, a citizen of the United States, residing at St. Louis, Missouri, have invented a certain new and useful Improvement in Car-Heaters, of which the following is a full, clear, and exact description, such as will enable others skilled in the art to which it appertains to make and use the same, reference being had to the accompanying drawings, forming part of this specification.

My invention relates generally to heating appliances and more particularly to a heater intended for use upon street, interurban and railway passenger cars, my present invention being an improvement on the form of car heater disclosed in my copending application filed February 27, 1918, Serial Number 219,414.

20 The principal objects of my present invention are, to generally improve upon and simplify the construction of the heater disclosed in my application aforesaid; to provide a comparatively simple heater which can be easily and cheaply manufactured, effective in service and economical in fuel consumption; and further, to provide a heater which utilizes oil as fuel, thereby eliminating the smoke, dust and gas that is developed in 30 heaters utilizing coal as fuel.

Further objects of my invention are, to provide a car heater which is very compact, occupies relatively little space on the car, and further, to utilize in connection with the 35 heater, an electrically operated fan which by suction draws fresh air into the heater and after said air has become heated, forces the same through distributing pipes leading to the interior of the car.

40 With the foregoing and other objects in view, my invention consists in certain novel features of construction and arrangement of parts, hereinafter more fully described and claimed, and illustrated in the accompanying 45 drawings, in which—

Figure 1 is a vertical section taken through the center of a car heater of my improved construction, and looking toward the rear wall thereof.

50 Fig. 2 is a vertical section taken approximately on the line 2—2 of Fig. 1.

Fig. 3 is a horizontal section taken approximately on the line 3—3 of Fig. 1.

Fig. 4 is a horizontal section taken approximately on the line 4—4 of Fig. 1. 55

Referring by numerals to the accompanying drawings which illustrate a practical embodiment of my invention, 10 and 11 designate respectively the top and bottom plates of the heater, the same being preferably 60 cast and rectangular in form, and formed in the top plate is an air inlet opening 12 to which is connected in any suitable manner a fresh air conveying pipe or conduit 13.

Arranged between the top and bottom 65 plates and secured to the marginal edges thereof in any suitable manner is the outer shell or housing of the heater, the same being preferably formed of sheet metal and bent to form a front wall 14, rear wall 15 70 and side walls 16 and 17. Arranged within this outer shell or housing adjacent to the side walls 16 is a vertically disposed partition 18, the same extending from front wall 14 to rear wall 15 and from top plate 75 10 to bottom plate 11. A part of the lower portion of this vertically disposed partition projects inwardly as designated by 19 to form a pocket 20, the same communicating with the space 21 between said partition 18 and the adjacent side wall 16. 80

Formed in the side wall 16 directly opposite this pocket 20 is an opening through which projects a fan housing 22, the outer edge of which is provided with a flange 23 85 which bears directly against the outer face of wall 16 around the opening therein. Secured in any suitable manner to this flange 23 is the edge of a plate 24, preferably cast, and provided near its center with 90 a bearing 25 for a fan shaft.

Formed in the inner wall of the housing 22 is an opening 26, the same establishing communication between the pocket 20 and the chamber within the fan housing. 95

The fan housing 22 is provided on one side with an angular extension 27, the same communicating with an opening 28 formed through plate 24, and which opening communicates with a hot air pipe or conduit 29, 100 the latter leading to the interior of the car with which my improved heater is associated.

A suitable suction fan 30 is positioned within fan housing 22, the shaft of said fan 105 being journaled in bearing 25. This fan

shaft is driven in any suitable manner, preferably by means of a small electric motor 31, which latter is mounted on a suitable bracket or support 32 that is secured to and projects 5 outwardly from plate 24.

Located adjacent to the side wall 17 is a vertically disposed partition wall 33 and interposed between this wall and said side wall 17 is a vertically disposed partition wall 34, 10 the extreme lower portion of which is perforated as designated by 35. This arrangement provides a pair of relatively narrow vertically disposed chambers 36 and 37 adjacent to side wall 17, said chambers having 15 communication through the perforations 35.

Located adjacent to front and rear walls 14 and 15 are vertically disposed partitions 38 and 39 respectively, the same extending from partition 18 to the side edges of partition 34. The lower portions of these partitions 38 and 39 are perforated as designated by 40.

Arranged adjacent to the partitions 38 and 39 are vertically disposed partitions 41 and 42 respectively, the same extending from partition 18 to partition 34. This arrangement provides relatively narrow chambers 43 between the walls 14 and 38 and 15 and 39, said chambers communicating with the 30 chamber 36.

The narrow chambers 44 have communication with the chamber 37 but are cut off from chamber 36 by relatively narrow strips 45 which are vertically disposed between the 35 righthand side edges of partitions 38 and 41 and 39 and 42. A horizontally disposed partition 46 is arranged a short distance below top plate 10 and extends from partition 18 to the top of partition 34 and from partition 40 41 to partition 42, and thus a relatively narrow horizontally disposed chamber 47 is formed between top plate 10 and said partition 46 and which last mentioned chamber communicates with chamber 36 at the top 45 thereof.

Leading from a suitable opening formed in partition 46 is an outlet or vent pipe 48 which is concentrically arranged within intake pipe 13. By this construction it will 50 be understood that the heat of the smoke and products of combustion which discharge through pipe 48 can be utilized in heating the fresh air entering through pipe 43.

Seated in the upper portions of partitions 55 18 and 33 are the open ends of horizontally disposed tubes 49 through which air may pass from chamber 37 to chamber 21. Located below these tubes and in the chamber between the lower portions of walls 18, 33, 60 41 and 42 is a suitable burner 50 for gas or liquid hydrocarbon, the supply pipe for which burner passes through the base plate 11 or through the rear wall 15 and partitions 39 and 42, and formed through the front 65 wall 14 and partitions 38 and 41 is an open-

ing in which is located a door frame 51. This door frame is preferably located below the lowermost row of tubes 49 in order that access may be readily had to the chamber in which the burner 50 is located.

Hinged to this frame 51 is a door 52.

During the operation of my improved heater, the flames from burner 50 will effectively heat practically the entire body of the heater and particularly the upper portion including the horizontally disposed tubes 49. As motor 31 is operated, fan 30 will be driven at a comparatively high rate of speed, thereby creating a suction of air through pipe 13 and this incoming air will so to a large extent absorb whatever heat which would otherwise be carried off by the smoke and products of combustion passing through outlet pipe 48. The incoming air passes through chamber 47; from thence into 85 chamber 36; thence downwardly through said last mentioned chamber and the chambers 43; thence through the perforations 35 and 40 in the lower portions of partitions 34, 38 and 39; thence upwardly through 90 chambers 37 and 44; thence through the rows of horizontally disposed tubes 49; thence downward through chamber 21 into pocket 20; thence through opening 26 into and through the chamber within fan housing 22; and from thence into and through 95 distributing pipe 29 leading to the interior of the car.

In thus passing through the heater, the air will become heated to a considerable degree and in such condition will be forced 100 into the distributing pipe or pipes leading through the car.

One of the particularly desirable features of my improved heater is the arrangement 105 and manner of mounting the fan housing, for it will be readily observed that the entire housing, the fan and the motor can be easily and quickly detached from the heater by withdrawing the bolts which secure the 110 edge of plate 24 and said fan housing to the wall 16.

A heater of my improved construction is relatively simple, can be easily and cheaply manufactured, is very compact, is economical in point of fuel consumption, and by using a fan to produce suction of air into and through the heater, the latter is very effective in operation.

It will be readily understood that minor 120 changes in the size, form and construction of the various parts of my improved heater may be made and substituted for those herein shown and described, without departing from the spirit of my invention, the scope of 125 which is set forth in the appended claims.

I claim:

1. In a car heater, a heater body in the form of a housing, partitions arranged therein to form a series of communicating air 130

- circulating chambers, a series of open tubes seated in certain of the partitions to establish communication from one heating chamber to another, a burner arranged below said tubes, a fan housing removably positioned in one of the outer walls of the heater body, said fan housing being provided with an opening which communicates with one of the air circulating chambers within the heater, a suction fan within said fan housing, and a motor carried by said fan housing and connected to said fan.
2. In a car heater, a heater body in the form of a housing including a top plate, a series of partitions arranged therein to form communicating air circulating chambers, there being an air inlet opening in the top plate of said housing, which opening communicates with one of the air circulating chambers, a burner arranged in the lower portion of said heater, one of the partitions within said heater being provided in its lower portion with a pocket, there being an opening in the outer wall of the heater body opposite said pocket, a housing positioned in said opening and projecting into said pocket which housing is bodily removable from said pocket, said housing being provided with air inlet and outlet openings, a suction fan mounted for operation within said housing, and a motor carried by and arranged on the exterior of said fan housing and directly connected to said fan.
3. In a car heater, a heater body in the form of a housing, partitions arranged therein to form two air circulating chambers on three sides of the housing and a single air circulating chamber on the fourth side of said housing, certain of which partitions are perforated to establish communication between the air circulating chambers, a plurality of horizontally disposed pipes arranged in the upper portion of the heater for establishing communication between the inner one of the pair of air circulating chambers and the single air circulating chamber, a fan housing removably seated in one of the walls of the heater housing and projecting into the single air circulating chamber, said fan housing being provided with inlet and outlet openings, a suction fan mounted for operation within said fan housing, and a motor carried by and arranged on the exterior of said fan housing and directly connected to said fan.

In testimony whereof I hereunto affix my signature, this 17th day of May, 1918.

JAMES J. ROHAN.
